UNITED STATES PATENT OFFICE.

CLARENCE CARSON, OF NEW ROCHELLE, NEW YORK, ASSIGNOR TO H. W. JOHNS-
MANVILLE COMPANY, A CORPORATION OF NEW YORK.

COMBINED SPEEDOMETER AND ODOMETER.

1,319,203.

Specification of Letters Patent. Patented Oct. 21, 1919.

Application filed October 16, 1915, Serial No. 56,203. Renewed November 16, 1918. Serial No. 262,905.

To all whom it may concern:

Be it known that I, CLARENCE CARSON, a citizen of the United States, and resident of New Rochelle, in the county of West-
5 chester and State of New York, have invented certain new and useful Improvements in Combined Speedometers and Odometers, of which the following is a specification.

10 My invention relates in general to a combined speedometer and odometer and particularly relates to standard units designed to be assembled to form such an instrument.

It has been usual in this art to design
15 speedometers, odometers and other rotary indicative instruments to meet the demands of the trade for different sizes and types of such articles.

One of the objects of my invention is to
20 construct a mechanical part, together with its carrying frame, of one standard size forming a unit which can be carried in stock. With these units there is also to be carried in stock, inclosing casings of different
25 standard sizes and reading dials of different standard sizes provided with fields of different diameters and different range of miles, each designed to coact with the standard mechanical unit.

30 A further refinement of the invention is to provide the mechanical unit of two separable parts, one part including the odometer mechanism and the other part including the speedometer mechanism, said parts being interchangeable respectively, with similar parts carrying different types of speedometer and odometer mechanism.

35 With this interchangeability of unit parts carried in stock, it is possible when an order
40 is received for a certain character of instrument to take one of these mechanical units, as assembled, or to construct the desired type of unit by assembling the desired type of the speedometer mechanism with the desired type of odometer mechanism, set the parts of the mechanism unit for insulation in the required sized casing or to fit the required sized dial or scale and then assemble the units. In this way any size or type of
45 instrument, can be supplied from stock, provided the required sized substantially cylindrical casing, dial or type of mechanism is available.

50 This I am enabled to attain, with the device hereinafter described, simply by shift-

ing some minor part or parts of the mechanical structure and by properly mounting the same in the desired type of casing.

Various other objects and advantages of the invention will be in part obvious from 60 an inspection of the accompanying drawings and in part will be more fully set forth in the following particular description of one form of mechanism embodying my invention, and the invention also consists 65 in certain new and novel features of construction and combination of parts herein-after set forth and claimed.

In the accompanying drawings:

Figure 1 is a front view of a preferred 70 embodiment of my invention with the dial removed and certain parts broken away to show internal construction;

Fig. 2 is a view similar to Fig. 1 showing the mechanical unit mounted in a casing 75 larger than the casing shown in Fig. 1;

Fig. 3 is a front elevation of the complete device shown in Fig. 1 or 2;

Fig. 4 is a transverse sectional view taken on the line 4—4 of Fig. 1; 80

Fig. 5 is a perspective view of the under-side of the device shown in Fig. 1 and with the frame removed from the containing casing; and

Fig. 6 is a similar view showing the frame 85 inserted in the casing.

In the following description and in the claims, parts will be identified by specific names for convenience of expression, but they are intended to be as generic in their 90 application to similar parts as the art will permit.

In the drawings there is shown a mechanical unit comprising two readily separable parts demountably fastened together and 95 hereinafter, for convenience of expression, referred to as a speedometer mechanism 10 and as an odometer mechanism 11. The speedometer mechanism includes a supporting frame 12 of any convenient configuration best suited for installation in the desired types of casing. The frame illustrated is shown to be a circular band provided with laterally extending and oppositely disposed supports 13 and 14 cast integral therewith and constituting a spacing means for localizing the units in a containing casing. The ends of the supports 13 and 14 are provided with tapped holes 100 adapted to receive, respectively, the pair 110

of screws 17 and 18, the former of which are designed to pass through the rear wall of the containing casing, hereinafter described, to fasten the unit thereto and the latter of which are adapted to fasten the odometer mechanism 11 demountably in position at the front of the completed instrument and spaced from the frame 12. The frame 12 is provided, at a point there-
10 in intermediate the supports, with an end thrust bearing 19 for a main driving shaft 20. A hub 21 for the shaft is positioned on the frame 12 diametrically positioned opposite the bearing 19. This hub projects externally of the outlines of the frame 12 and is provided with a reduced threaded portion 22, by means of which the device may be mounted in position, or by means of which, a container of the driving element may be
15 attached. The hub is internally threaded and contains a bearing block 23 in which the shaft 20 is mounted for free rotary movement. The outer end of the shaft extends beyond the hub and is designed to be operatively connected to any member, the speed of which is to be ascertained and the revolutions of which are to be counted. The driving shaft 20 constitutes a governor shaft and is provided with a centrifugally actuated governor, including weights 24, operatively connected to a runner 25 which is slidably mounted upon the governor shaft and which constitutes a speed control member of the device. The runner 25 is in the
20 form of a sleeve and is provided with a pair of laterally projecting disks 26 extending perpendicular to the axis of movement of the same and spaced apart longitudinally of said axis to form an annular runway 27 therebetween.

The indicator actuating mechanism of the speedometer mechanism is carried on a mounting plate 28 and is removable therewith from the frame 12, as a unit. As the indicator actuating mechanism may be of the same type for the different types of casings and for the different types of odometer mechanisms carried in stock, this mounting plate may also be utilized as the mounting plate for the odometer mechanism and each of the different odometer mechanism units may be provided with the same type of indicator actuating mechanism. In this way the odometer mechanism and the indicator actuating mechanism may be combined as one unit and at the same time retain the advantage of separating the speedometer parts more particularly pointed out in applicant's co-pending application Serial No. 32,254, filed June 10th, 1915. This indicator mechanism includes a pair of shafts journaled in the mounting plate 28 and in a bridge plate 29 affixed to the rear face of the mounting plate. One of the shafts 30 projects rearwardly through the bridge

plate upon which projected portion is a crank arm 31 adjustably fastened thereto by means of a collar 32 fastened to the shaft by a set screw 33. The crank includes an arm or stud 34 provided with a rounded head 35 adapted to be inserted in the runway 27, so that the longitudinal movement of the runner on the shaft will rock the crank on its shaft. The shaft 30 is enlarged between the plates 28 and 29 to prevent longitudinal movement thereof and the portion thereof adjacent the plate 28 has a sector gear 36 adjustably fastened thereto and designed to mesh continually with a small pinion 37 secured to the other shaft 38. A spring 39 has one end secured to a post 40 extending rearwardly from the mounting plate 28 and has its opposite ends attached to the notched extension 41 depending from the crank arm. The shaft 38 extends forwardly through the mounting plate 28 and constitutes an indicator actuating shaft. This shaft is designed to extend through an opening 42 in the dial plate 43 which dial plate is provided with a scale 44 arranged in an arc with the opening 42 concentrically disposed relative thereto. An indicator or pointer 45 is fixed to the shaft 38 by means of a hub 46 and is arranged to move relative to the scale as is usual with speedometers of this character.

The mounting plate 28 and the parts attached thereto constitute a complete odometer demountable as a unit from the casing. This mounting plate is provided with a pair of end brackets 47 fixed in position and formed preferably by cutting tongues from the body of the plate and bending these tongues at right angles thereto to form an elongated sight opening 48 centrally of the plate. Supported from and between these end brackets are numeral wheel units 49 of the Geneva type, coacting to form distance and trip indicator mechanism, more particularly described in my co-pending application Serial No. 33,255, filed June 10th, 1915. The odometer mechanism includes a control gear 50 driven from the shaft 20 within the casing by means of a demountable register mechanism driving shaft 51. The shaft 51 laps the shaft 20 and is driven therefrom by means of the intermeshing gearing 52. The rear end of the shaft 51 is mounted in end bearings 53 carried by the frame 12 and the forward end is mounted in bearings 54 formed in the removable mounting plate 28.

One of the supports 13 is provided with a boss 55 in which is mounted a reset mechanism 56 including a knurled setting wheel 57 for changing the reading of the odometer. This construction is more particularly defined in my co-pending application, Serial No. 34,344 filed June 16, 1915.

In the type of instrument illustrated in Fig. 1, the mechanism containing casing

is of a size designed so that the mechanical unit hereinbefore described shall have a snug fit therein. One side of the casing, for convenience referred to as the bottom 5 side, is provided with a recess 59 opening from the front edge thereof to receive the hub 21, which extends therethrough. A bottom portion of the frame 12 on opposite sides of the hub, is provided with a lateral 10 extension 60 opposite edges of which are provided with grooves 61 into which the edges forming the recess 59 has a sliding fit to position the unit in place in the casing. The side of the casing is also provided with 15 a recess 62, similar to the recess 59, for accommodating the projecting position of the reset mechanism 56.

In the modification illustrated in Fig. 2, the casing is shown to be of a larger diameter 20 designed to accommodate a larger dial plate, having a scale of correspondingly larger diameter. With a scale of this type, it is obvious that the indicator actuating 25 shaft must be moved so that it will rotate about an axis concentrically disposed relative to the arc of the scale. For this purpose, the mounting plate and bridge plate are provided with a plurality of aligned 30 small holes 63 constituting journal bearings for the indicator shaft. These bearings are concentrically disposed relative to the axis of the rotation of the shaft 30 and are positioned to the outside of the sector gear 36. Two of these bearings are illustrated in the 35 drawings and it is, of course, obvious that as many of these bearings may be provided as there are different sizes of dials to which the mechanical units are designed to coöperate.

Each of the dial plates 43 is provided with 40 an indicator shaft opening 64 designed to register with one of the bearings 63. The dial is also provided with fixed sight opening 65 designed, with the different type of units to register with the sight openings 45 48 in the supporting plate. The extension 60 is provided with a stud 66 adapted to engage a notch 67 at the bottom of the dial, thus providing a means for centering the dial relative to the frame 12. The different 50 cases are each provided with a glass retaining ring 68 for holding the front glass face 69 in position.

In operation, let it be assumed that a 55 mechanical unit of the class described is carried in stock, together with dials and casings of different sizes and types and with the indicator shaft openings in the dials differently positioned relative to a fixed point of reference, such as the recess 59 in 60 the casing. When an order is received for a certain size or type of instrument, the casing of that required size is assembled with one of the mechanical units of the desired type. The indicator actuator shaft 65 38 is adjusted in the particular bearing

which will register with the opening in the dial plate when the parts are assembled and the unit is inserted in the casing with its groove 61 containing the edges of the casing at the recess 59. Before the units are assembled the set screw 33 is loosened, if necessary, and the crank arm 31 adjusted on the shaft 30 until the head 35 has a slight bearing engagement with one of the disks 26. Then the gear 36 is adjusted on the shaft 70 51, if such an adjustment is necessary to preserve the meshing of the same with the pinion 37. The indicator is suitably adjusted on the shaft 38, the glass face is inserted in place and there is thus formed 75 80 a complete article of manufacture.

It may happen that an order is received for an instrument requiring an odometer mechanism differing from the odometer mechanism assembled with the speedometer 85 mechanism constituting the mechanical unit usually carried assembled in stock. If such should be the case, the speedometer mechanism is assembled with an odometer mechanism of the desired type and a plate 28, 90 provided with the desired odometer mechanism is positioned on the support 13 and fastened in place by the screws 18.

By means of a device of this character, it is possible to fill orders for a variety of 95 different size instruments from a minimum number of composite parts. The expensive mechanical inserts may all be made of one standard size, thus reducing the initial cost of construction and these different units 100 may be made to fit the desired size casings merely by shifting the position of the indicating actuator shaft. As all of the indicator actuating mechanisms are carried by the mounting plate, this plate and its attached parts may be readily removed as a unit thus providing ready access to the parts carried thereby. This ready demounting of the plate also provides ready access to the odometer mechanism thus permitting 105 110 the regrouping of indicator mechanism as pointed out in the above identified application, Serial Number 33,255, filed June 10th, 1915.

While the sight openings 65 have been 115 defined as fixed relative to some point of reference such as the stud 66 it is obvious that in those conditions where the odometer mechanism is otherwise positioned relative to the dial, dials with differently positioned openings may be carried in stock and utilized, but usually it is immaterial as to where the odometer sight opening is positioned. It is no objection that it is spaced from the center of the dial in some cases 120 125 more than in others.

While I have shown and described, and have pointed out in the annexed claims, certain novel features of my invention, it will be understood that various omissions, 130

substitutions and changes in the form and details of the device illustrated and in its operation may be made by those skilled in the art without departing from the spirit of the invention.

5 Having thus fully described my invention, I claim:

1. In a device of the class described, the combination with a dial provided with an odometer sight opening and with an indicator shaft opening, of an odometer mechanism constituting a demountable unit including a support provided with a plurality of bearings, one of which is adapted to 10 register with said indicator shaft opening when the dial is assembled in operative relation to the disk with the numeral wheel units of said odometer mechanism opposite said sight opening, a speedometer mechanism including an indicator shaft adapted to 15 be mounted in any one of said bearings, an indicator fixed to said shaft and movable over said dial and a rotary driving mechanism operatively connected to said odometer mechanism and to said speedometer mechanism to actuate the same.

2. In a device of the class described, the combination with a casing and a dial having an opening therethrough, of a mechanical unit designed to be assembled with 20 similar casings of different sizes and with the dial openings differently positioned, said unit including an odometer mechanism, and a speedometer mechanism, said speedometer mechanism including an indicator shaft 25 shiftable relative to the unit to extend through the differently positioned openings in the different dials and driving mechanism mounted in the unit in relatively fixed 30 position, means connecting said driving mechanism with said odometer mechanism to actuate the same and means for connecting 35 said driving mechanism with said speedometer mechanism to actuate the same, said speedometer mechanism including a shiftable driving connection with the indicator shaft.

3. In a device of the class described, the combination with a casing provided with 40 two openings and means adjacent one of the openings for attaching the same to mechanical units of different sizes relative to the size of said casing, of a mechanical unit adapted to be inserted into said casing 45 and provided with means coacting with said first named means for fastening the same in place in fixed relation thereto, said unit including a speedometer mechanism, a shaft for driving the same positioned in 50 one of said openings, an odometer driven from said shaft, said odometer including means projecting therefrom positioned in the other of said openings assisting to locate the unit in position in the casing.

65 4 In a combined speedometer and odom-

eter, the combination of a mechanical unit having a rotary driving element, an odometer mechanism operatively connected to said driving element and including numeral wheels, an indicator shaft shiftable into a 70 plurality of different positions in said unit, a speed controlled mechanism operated from said driving element and actuating said indicator shaft in all positions of the same, and a casing for accommodating said unit, 75 said casing being provided with set spaces for accommodating said numeral wheels of the odometer and for accommodating said shiftable indicator shaft when in that one of its different positions designed for the same 80 when the indicator element is set in its proper position.

5. In a device of the class described, a mechanical unit constituting a complete article of manufacture designed to be mounted in 85 a containing casing and comprising a frame, a driving shaft mounted on said frame, an odometer mechanism operatively connected to be actuated from said driving shaft, and a speed indicating mechanism operatively 90 connected to be actuated from said shaft and means carried by the unit for mounting the same in a definite position in a containing casing.

6. In a device of the class described, a mechanical unit designed to be mounted in a containing casing and comprising a support, a driving shaft mounted for rotary movement in said support, a speed indicating mechanism operatively connected to said 95 shaft, a mounting plate removably affixed to said support, an odometer mechanism supported from said plate and removable as a unit therewith, and means operatively connecting said shaft with said odometer mechanism.

7. In a device of the class described, a mechanical unit comprising a frame, a driving shaft mounted for rotary movement in said frame, a speed controlled mechanism operatively connected to said shaft to be actuated thereby, a mounting plate removably affixed to said support, an indicator actuating mechanism supported from said plate and operatively connected to said speed 110 controlled mechanism, an odometer mechanism carried by said plate, means operatively connecting said shaft with said odometer mechanism, said indicator actuating mechanism and said odometer mechanism being 115 both removable with the plate without disturbing either the mechanism carried by the plate or the speed controlled mechanism.

8. In a device of the class described, a mechanical unit comprising a frame provided with means for positioning the same in an inclosing casing, an odometer mechanism including an indicator element set in fixed position in the unit, and a speedometer mech- 125 130

- anism including an indicator shaft mounted in said frame, said shaft being shiftable so as to be disposed in definite position relative to the inclosing casing.
- 5 9. In a device of the class described, the combination of a mechanical unit including an odometer mechanism and a speedometer mechanism, an inclosing casing for said unit, said casing provided with a sight opening 10 for the odometer mechanism and provided with a second opening for an element of the speedometer mechanism, said element being shiftable in the unit to position the said element in said second opening in the casing.
- 15 10. An article of manufacture comprising two standard units, one of said units constituting a unitary mechanism including a

complete odometer mechanism and a complete speedometer mechanism, the other unit constituting an inclosing casing for said unitary mechanism, said unitary mechanism including means for assembling the same in operative relation in said casing.

11. An article of manufacture comprising two standard units, each complete in itself, 25 one of said units comprising a speedometer mechanism and the other unit comprising an inclosing casing and coacting means carried by the units for assembling the same to form a complete article.

Signed this 2nd day of September, A. D. 30
1915.

CLARENCE CARSON.
